United States Patent Office.

CHARLES F. RAVN, OF MILWAUKEE, WISCONSIN.

Letters Patent No. 77,656. dated May 5, 1868.

IMPROVEMENT IN WAGON-SKEIN.

The Schedule referred to in these Letters Patent and making part of the same.

TO ALL WHOM IT MAY CONCERN:

Be it known that I, CHARLES F. RAVN, of the city and county of Milwaukee, and State of Wisconsin, have invented a new and useful Improvement in Wagon-Skeins; and I do hereby declare that the following is a full, clear, and exact description thereof, which will enable those skilled in the art to make and use the same, reference being had to the accompanying drawing, forming part of this specification, in which—

Figure 1 is a perspective view of the skein and box.

Figure 2, a longitudinal sectional view of same.

Figure 3, cross-section.

Similar letters of reference in each of the figures indicate corresponding parts.

The object of my invention is to construct a wagon-skein from cast iron, in such manner that it shall be durable, simple, and economical, easily manufactured, and easily repaired when any of the parts are worn out, broken, or lost, each piece being perfect when taken from the sand, requiring no finishing for use.

A is the wooden axle; B, the skein; C, wagon or axle-box, cast with an inside projection at the small end, and without any projection at the large end. An enlargement of the skein next the shoulder, when the skein is in the box, forms a recess for lubricating-material around the skein in the centre of the box. D, centre-iron; E, bolt through skein B, wood A, and centre-iron D, holding them firmly together; F, lynchpin; G, nut on end of centre-iron D; H, cap, with shoulder, through which passes the lynchpin, holding the wheel on the axle.

Operation.

The wooden axle being made tapering at the ends, to fit skein B, iron, D, is fitted into same. The skein is then slipped on to the axle, and bolt E driven through, and riveted at each end. The bolt-holes on both sides of the skeins are countersunk, so that when the bolt is riveted, its ends will be just even with the outer surface of the skein. The nut G is then screwed on solid, making an additional security, holding skein on the axle. It is designed that, in practice, iron, D, in some cases, will be let into the side of the axle, and extend back towards the centre of the axle, behind the inner end of the skein, and bolted to the axle at that point. Cap H is then put on, and lynchpin F inserted, and the skein is ready for use.

What I claim as my invention, and desire to secure by Letters Patent, is—

Skein B, centre-iron D, bolt E, lynchpin F, nut G, and cap H, in combination, substantially as and for the purpose described.

C. F. RAVN.
